(57) **CLAIM**

The ornamental design for a filter for removing particle matter, as shown and described.

DESCRIPTION

FIG. 1 is a perspective view of a filter for removing particle matter illustrating my new design;

FIG. 2 a front view thereof;

FIG. 3 is a rear view thereof;

FIG. 4 is a top view thereof, the bottom view thereof being a mirror image;

FIG. 5 is a right view thereof, the left view thereof being a mirror image;

FIG. 6 is an enlarged view delimited by the four lines labelled 6 in FIG. 2;

FIG. 7 is a cross-sectional view taken through line 7-7 of FIG. 2;

FIG. 8 is a cross-sectional view taken through line 8-8 of FIG. 6 with the middle section omitted; and,

FIG. 9 is an enlarged view delimited by the four lines labelled 9 in FIG. 3.

The broken lines in the drawings represent unclaimed subject matter.
